UNITED STATES PATENT OFFICE.

PAUL WOLKOGON-WOLYNSKI, OF BIELEFELD, GERMANY.

CUTTING MACHINE.

Application filed November 6, 1925, Serial No. 67,307, and in Germany November 6, 1924.

Shaped leather pieces for soles, heels and the like were hitherto mostly made in manufacturing works by means of extensive and costly machines. In small shoemakers' 5 workshops or shoe repair shops, such shaped pieces were generally cut by hand with the aid of an appropriate knife, which results however in a considerable waste of material, while said cutting could mostly be done 10 by strong and skilled persons only.

The present invention provides an improved machine for cutting such shaped leather pieces, the novelty consisting mainly in the fact that the pressure-bar of said 15 machine carrying the cutter of the same is directly pivoted to a pressure-lever so as to be movable over the table of the machine.

The accompanying drawing illustrates the improved machine: Fig. 1 is a side view partially shown in cross-section, Figs. 2 and 3 are respectively a longitudinal section and a cross-section through the lower end of the pressure-bar with the cutter, while Figs. 4 and 5 are cross-sectional views of the upper 25 end of the pressure-bar.

The machine comprises a table *a* having an integral upwardly projecting bracket *b*. Said table carries a wooden insertion *c* with a slightly concave upper surface. In the 30 upper end of the bracket *b* a two-armed lever *d* is fulcrumed and at its rear arm *d*¹ acted upon by a draw-spring *e* tending to pull said arm continuously downwards, while its front arm is at its end connected 35 by a chain *f* or the like with a treadle *g* linked to the foot of the table *a*. The cutter *i* with straight cutting-edge is detachably fixed in a holder *h*, that is loosely mounted on the lower guide-bolt *k* of a presser-bar 40 *m*, which is pivoted at its upper end by a ball-joint *n* in a bearing *o* of the lever *d* so as to be movable over the concave wooden insertion *c*. To permit, after complete depression of the lever and thus of the cutter 45 *i*, the latter returning automatically to its raised position, a bolt *r* in the holder *h* that

is spring-pressed at *p* is formed with an elongated slot therein mounted over a guide-pin *s* in such a way that the cutter is prevented from slipping along the table *a* or the 50 work-piece thereon. The bracket *b* carries near its top end a fixed abutment *t* that serves to limit the downward movement of the pressure-arm *d* and thus the stroke of the cutter *i*, which thereby penetrates the 55 wooden insertion *c* for a very shallow depth only.

Besides, the loose guiding of the holder *h* on the lower guide-bolt *k* of the pressure-bar *m* permits an adjustment of the cutter 60 *i* in any direction and thus to any desired angle, so that the cutting work is considerably facilitated and can be carried out by unskilled persons.

What I claim is:

1. In a machine for cutting shaped leather pieces, the combination of a table and an integral bracket thereon, a pressure-lever fulcrumed on said bracket, a pressure-bar at its upper end pivoted to said pressure-lever 70 so as to be movable over the whole table and adapted to be depressed by said lever and a cutter on the lower end of said pressure-bar, substantially as set forth.
2. In a machine as specified in claim 1, a 75 guide-bolt on the lower end of said pressure-bar, and a holder for said cutter loosely mounted on said guide-bolt so as to be turnable thereon, substantially as set forth.
3. In a machine as specified in claim 1, 80 a guide-bolt on the lower end of said pressure-bar, a holder for said cutter loosely mounted on said guide-bolt so as to be turnable thereon, and means to automatically return said cutter to its raised position after 85 complete depression of said pressure-bar, substantially as set forth.

In testimony whereof I have hereunto set my hand in the presence of two subscribing witnesses.

PAUL WOLKOGON-WOLYNSKI.
